US00D982545S

(12) **United States Design Patent** (10) **Patent No.:** **US D982,545 S**
(45) **Date of Patent:** **** Apr. 4, 2023**

(54) **SERVO AMPLIFIER**

- (71) Applicant: **Mitsubishi Electric Corporation**,
Tokyo (JP)
- (72) Inventors: **Hiroyuki Kato**, Tokyo (JP); **Kentaro Tsukamoto**, Tokyo (JP); **Masahiro Ichikawa**, Tokyo (JP); **Hanako Kondo**, Tokyo (JP); **Tetsuya Okuda**, Tokyo (JP); **Satoshi Akatsuka**, Tokyo (JP); **Takumi Aikawa**, Tokyo (JP); **Yusuke Ueda**, Tokyo (JP)
- (73) Assignee: **Mitsubishi Electric Corporation**,
Tokyo (JP)

(**) Term: **15 Years**

(21) Appl. No.: **29/741,290**

(22) Filed: **Jul. 10, 2020**

(30) **Foreign Application Priority Data**

Jan. 30, 2020 (JP) ..... 2020-001602 D

(57) **CLAIM**

The ornamental design for a servo amplifier, as shown and described.

DESCRIPTION

FIG. 1 is a front, top and right side perspective view of a servo amplifier, showing a first embodiment of our new design;

FIG. 2 is a rear, bottom and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, top and right side perspective view of a servo amplifier, showing a second embodiment of our new design;

FIG. 10 is a rear, bottom and left side perspective view thereof;

FIG. 11 is a front view thereof;

FIG. 12 is a rear view thereof;

FIG. 13 is a top view thereof;

FIG. 14 is a bottom view thereof;

FIG. 15 is a right side view thereof; and,

FIG. 16 is a left side view thereof.

The parts shown in the broken lines do not form part of the claimed design.

1 Claim, 16 Drawing Sheets
